[57] CLAIM

The ornamental design for a motorcycle saddle bag, substantially as shown and described.

DESCRIPTION

FIG. 1 is a perspective view of a motorcycle saddle bag, showing our new design;

FIG. 2 is a front elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a perspective view of a motorcycle saddle bag showing a second embodiment of my new design;

FIG. 8 is a front elevational view of the embodiment of FIG. 7;

FIG. 9 is a right side elevational view of the embodiment of FIG. 7;

FIG. 10 is a rear elevational view of the embodiment of FIG. 7;

FIG. 11 is a top plan view of the embodiment of FIG. 7; and

FIG. 12 is a bottom plan view of the embodiment of FIG. 7.
